UNITED STATES PATENT OFFICE.

ALBERT G. EMERY, OF NEW YORK, N. Y., ASSIGNEE TO THE GOODYEAR'S METALLIC RUBBER SHOE COMPANY, A CORPORATION OF CONNECTICUT.

IMITATION-LEATHER SHOE AND PROCESS OF MANUFACTURING THE SAME.

1,280,197.

Specification of Letters Patent.

Patented Oct. 1, 1918.

Application filed December 5, 1917. Serial No. 205,523.

To all whom it may concern:

Be it known that I, ALBERT G. EMERY, a citizen of the United States, residing at New York, county of Bronx, and State of New York, have invented certain new and useful Improvements in Imitation-Leather Shoes and Processes for Manufacturing the Same, of which the following is a full, clear, and exact description.

10 This invention relates to imitation leather shoes and processes for manufacturing the same. It is more particularly directed to a shoe of the kind described made up largely of rubber and rubberized fabric and to a process for the manufacture of such a shoe.

Rubber as a substitute for leather in footwear possesses two major advantages namely, its relatively low cost and its water-proof quality. It possesses, however, one 20 disadvantage viz., its low transpirational factor. The principal object of the present invention accordingly is to overcome this defect while providing a shoe having the appearance and in general the easy and comfortable wearing characteristics of a leather shoe. Another object is to provide a simple process for the manufacture of such an article.

Briefly, the article forming part of the invention consists of a shoe comprising a top 30 of transpirational material secured to a rubber upper, a loose lining, an insole and an outsole, the extremities of the upper being lapped over the edge of the insole and lining and secured thereto. This construction has 35 been found to possess the desired characteristics set forth among the objects above.

In the accompanying drawing wherein a shoe constituting one embodiment of the 40 article forming part of the invention is shown—

Figure 1 represents a side elevation of the shoe;

Fig. 2 represents a median longitudinal 45 sectional elevation thereof with the thickness of the layers exaggerated in order to set forth the construction more clearly; and

Fig. 3 is a fragmentary detail of the material employed for the rubber upper.

50 Referring now more particularly to the drawings, 1 indicates a top consisting of transpirational material such as the ordinary form of cloth employed in shoe manufacture. To the top is attached the usual form of tongue 2, preferably consisting of

a rubber composition. The top as shown in this embodiment terminates just below the upper edge of a rubber upper 3, the outer face of the top being secured to the inner face of the upper by rubber cement and forming a lapped joint therewith. The material constituting the upper possesses in general the characteristics of leather. Its feel and appearance are those of leather as also its flexibility. As shown more clearly in Fig. 3, the material consists of a fabric layer 4 intermediate layers of rubber composition 5 and 6. By embedding the fabric in this manner it has been found possible to employ a relatively thin layer of fabric without sacrificing the wear-resisting properties of the material. Such embedded fabric has been found to have substantially as much strength as far heavier fabric coated on one side and possesses the advantage that there is no danger of separation between the parts as in the case of heavy fabric in which the parts are cemented together. The use of two layers of rubber with an intermediate fabric as employed in the present construction, also possesses an advantage in that it prevents raveling of the fabric at exposed edges.

The interior of the shoe is provided with a loose lining 7 of any suitable material preferably a light form of cotton fabric. The lining is secured preferably by cement along the edges of the top and along the line of the junction of the quarters. It also lies loosely over the inner surface of the upper, its lower edges being fastened as indicated below.

The shoe is provided with the usual form of insole 8 and filler soles 9 upon which is placed a welt sole 10 to which is attached the heavy rubber outsole 11.

As shown more clearly in Fig. 2, the extremity of the rubber upper is lapped over and secured by cement to the surface of the lining which lies over the insole and between the insole and outsole. This method of securing the parts mentioned provides a joint similar to that in a leather shoe. Toe-caps, shank-stiffeners and counter-pieces may be applied if desired. The reinforcing strip 12 placed at the junction of the quarters of the top is extended under the upper to a position between the insole and the heel.

A shoe made in accordance with the above construction, while composed of an upper having an outer surface of rubber stock re-

inforced with fabric, nevertheless has the appearance in general of a leather shoe. The sole projects from the upper tangentially and forms a sharp angle therewith, somewhat similar to a leather shoe; but is secured to the upper by vulcanization to form a unitary structure. The shoe also permits of a high degree of transpiration and may be worn with as much ease and comfort as a leather shoe. The degree of transpiration is, of course, affected by the quality of the top but the special provision which provides transpiration resides in the loose lining. Specifically the loose lining has the following advantages: (1) The fibers of the fabric are free to exercise their absorptive and capillary properties which is not the case where the lining is adherent as in the usual rubber shoe. Due to the ability to exercise the absorptive and capillary properties the lining is adapted to provide ventilation; (2) the loose lining permits conformation to the positions assumed by the foot, that is, the lining has a certain amount of "give" and is more comfortable than the usual adherent lining; (3) it will be observed further that the lining also serves to cover the joint between the top and upper thus preventing the chafing of the wearer's foot by contact of the sharp edge of the upper therewith.

In carrying out the process in its preferred form, the top lining, upper, tongue, etc., are cut out in the usual manner practised with leather by a die or knife, the parts being shaped similarly to the parts of the leather shoe. The top and lining are united by the use of cement or otherwise as desired and as assembled are drawn over and fitted by rolling to the last upon which the insole has been previously applied. It will be noted that the lining extends completely about the last and that the top extends over only a portion of the surface of the last, terminating at a position to be attached to the upper edge of the upper. This construction differs from the usual rubber arctic, for example in that the cloth top is co-extensive with the lining and is secured in place therewith.

with by the insole after the top and lining have been secured in place. The vamp or upper is applied and its upper edge is secured to the lower edge of the top by cement and subsequent rolling. The rag soles, welt sole, and outsole are applied in the usual manner and the shoe is removed from the last and vulcanized.

As many apparently widely different embodiments of this invention may be made without departing from the spirit thereof, it is to be understood that I do not intend to limit myself to the specific form of the invention as set forth except as indicated in the appended claims.

Having thus described my invention, what I claim and desire to protect by Letters Patent is:

1. An imitation leather shoe, comprising a rubber upper, a top of material adapted to permit transpiration terminating just below the upper edge of and cemented to the rubber upper, a loose lining, an insole and an outsole, the extremities of the upper being lapped over and secured to the lining between the insole and outsole.

2. An imitation leather shoe, comprising a fabric top, a rubberized fabric upper, said top terminating just below the upper and secured thereto by rubber cement, a loose lining adapted to permit transpiration, an outsole and an insole, said upper being lapped over and secured to the lining by cement between the insole and outsole.

3. A process of the kind described, which comprises assembling a top of material adapted to permit transpiration with a loose lining also adapted to permit transpiration, fitting the so assembled parts over a last having an insole applied thereto, securing a rubber upper by cement to the top while preserving the lining loose, lapping and securing the edges of the upper over the lining and insole therebeneath and fixing a second sole over the insole and secured upper.

Signed at New York, county and State of New York, this 12th day of November, 1917.

ALBERT G. EMERY.
